UNITED STATES PATENT OFFICE.

HERBERT C. WARREN, OF HARTFORD, CONNECTICUT.

PRECISION-INDEX.

SPECIFICATION forming part of Letters Patent No. 531,817, dated January 1, 1895.

Application filed April 11, 1894. Serial No. 507,133. (No model.)

To all whom it may concern:

Be it known that I, HERBERT C. WARREN, a citizen of the United States, residing at Hartford, in the county of Hartford and State of Connecticut, have invented certain new and useful Improvements in Precision-Indexes, of which the following is a specification.

This invention relates to machines for the manufacture of precision-indexes, the object 10 of the invention being to furnish an improved machine adapted for producing corrected or precision indexes of the class used on gear-cutting and graduating-machines, and for astronomical instruments and like purposes, 15 with economy and rapidity and with the utmost accuracy.

In the drawings accompanying and forming a part of this specification, Figure 1 is a plan view of one form of machine embodying my 20 improvements and adapted for carrying out my invention. Fig. 2 is a side elevation of the same, the cutter for graduating or cutting the index-blank being shown in an elevated position out of contact with said blank. Fig. 25 3 is a vertical longitudinal section taken in line 3-3, Fig. 1. Fig. 4 is a horizontal cross-section of a portion of the machine, taken in line 4-4, Fig. 3, a portion of the master-index being broken away to more clearly illustrate certain of the details. Fig. 5 represents a table 30 of determined errors, showing the ascertained differences in plus or minus as between the approximately correct divisions of the master-index and the divisions of a correct, or precision, index.

Similar characters designate like parts in all the figures.

My improved machine for the manufacture of precision indexes, in the preferred embodiment thereof herein shown, comprises a bed or frame work for supporting the operative details of the mechanism, a work-carrying spindle adapted for carrying a master-index and a blank from which a corrected or precision-index is to be made, a master-index approximately divided into a given number of aliquot parts, each of which parts has a working face, a normally fixed reference point or scale, and a reading indicator in position and adapted for 40 being shifted from and into bearing engagement with the successive working faces of the master-index and adapted to be read in con-

nection with said reference point or scale, all of which will be hereinafter more fully described.

In the drawings, the bed of the machine, which, in practice, may be of any suitable form adapted for carrying the operative parts, is designated in a general way by B.

The work-carrying spindle, designated by 60 S, is shown supported in a bearing, 2, formed preferably integral with the bed or frame of the machine, after a well-known manner. The spindle S is shown provided with a worm-wheel, 3, rigidly fixed thereon in a manner 65 hereinafter more fully described, whose teeth mesh with the threads of a worm, 4, which is carried by a shaft, 5, that is supported in bearings, 6 and 6', upon the bed B of the machine. This worm-shaft is shown furnished with a 70 hand-wheel, 7, whereby the same may be revolved for turning the worm-wheel, and through this the work-carrying spindle and parts carried thereby.

In the form thereof herein shown, the worm-wheel is connected indirectly to the work-carrying spindle, it being secured by means of screw-bolts to a master-index, C, which in turn is firmly secured to the work-carrying spindle, preferably by being driven thereon. 80 In this connection, it is desired to state that the master-index and the worm-wheel secured thereto may be fitted to rotate upon the work-carrying spindle, and said spindle may be non-rotatively fixed in the bed or frame of 85 the machine if desired, although the construction before described is preferable.

The master-index is herein shown as a discous plate radially divided peripherally by a series of notches, 8, to form a plurality of radially-disposed working-faces, 9, herein shown as twenty-four in number, the difference between successive bearing-faces representing approximately fifteen degrees and being designated, respectively, by the numerals 95 1 to 24 inclusive. Said master-index has a hub, 10, of considerable length, which engages the work-carrying spindle S and has a bearing at its lower end upon the upper end of the journal-bearing 2. The master-index, 100 which practically constitutes the "pattern" by means of which to approximately position the index-blank for graduating or dividing, may be constructed in any well-known man-

anner, and may be divided into any number of aliquot parts, which will depend upon the form of precision-index it is desired to make. After the master-index has been divided, as just described, to approximate precision, said index is measured or surveyed to accurately ascertain the errors in division with relation to a true standard, which errors are then registered or tabulated in proper order with relation to successive divisions of the index to designate the degree or extent of error, plus or minus, as compared with the precise division, which will be thoroughly understood by reference to Figs. 4 and 5 of the drawings.

The method *per se* of surveying the index-plate so as to obtain a true correction of the approximate divisions, is well known in the art to which this invention appertains, and it is therefore deemed unnecessary to enter into a detailed description of this method, which, it may be observed, is sometimes designated by mechanicians as "Troughton's method."

In practice, the index-blank, designated by 25 D, will preferably be secured to the spindle S above the master-index, as illustrated most clearly in Fig. 3 of the drawings, the said index-blank, master-index, worm-wheel 3, and spindle S being rigidly secured together in a 30 manner to prevent accidental movement of one part with relation to the other, the master-index and worm-wheel being either keyed to or driven upon the spindle S, and the precision-index blank being fitted to the upper end of the spindle and securely held in place by means of a nut, 11, at the upper end thereof, said index-blank D being supported at a suitable distance above the master-index by the hub 10 of the said master-index; or, these 35 parts may be firmly fixed to the work-carrying spindle by any well-known means for fixing wheels on shafts.

In connection with the foregoing, it is desired to state that the positions of the master-index and index-blank with relation to the spindle might be reversed, a corresponding re-arrangement of reading and dividing apparatuses being in such case made. The two plates or wheels, viz: the master-index and 45 index-blank, should, of course, be rigidly fixed or connected together preparatory to the operation of dividing or cutting said blank. This may be done by forming said two plates or wheels integral, by making them separate 50 and rigidly fixing them together, or by making them separate and separately fixing each one to the spindle.

As a means for dividing, cutting or graduating the periphery of the index-blank, especially when this is to have teeth cut therein after the manner represented in the drawings, I have provided a milling-cutter, 12, of a form 60 suitable for cutting the required tooth-space; which cutter is shown mounted upon an ordinary cutter-spindle, 13, that is carried in a bearing, 14, upon a slide, 15, that is mounted 65 upon vertical slide-ways, 16, formed upon a

carriage, 17, which is fitted for horizontal movement in slide-ways, 18, formed upon the bed of the machine, as will be clearly understood by reference to Figs. 1 to 4 of the drawings. A pulley, 19, may be fixed on said cutter-spindle as shown in Figs. 1, 2 and 3; or, said spindle may be driven through the intervention of gearing after a well-known manner for driving the cutters of dividing-engines and gear-cutting machines.

For the purpose of imparting to the cutter-wheels the required movement laterally of the index-blank, the cutter-slide is shown provided with a screw-threaded projection or nut, 20, engaging with a screw, 21, that is carried in a suitable bearing at the upper end of the carriage 17, as illustrated most clearly in Fig. 3, which screw may be operated by hand by means of the hand-wheel 22 secured to said screw 21; and as a means for imparting a movement to the cutter toward and from the axis of said blank, I have provided a screw, 23, journaled at its outer end in a suitable bearing, 24, upon the bed of the machine, and having its inner end fitted in a screw-threaded opening, 25, in the carriage 17, after the well-known manner of connecting feeding-devices with sliding carriages, said screw 23 being provided at its outer end with a hand-wheel, 26, by means of which the screw may be revolved to feed the carriage toward or from the work.

As a means for supporting and holding the index-blank during the cutting operation, the outer edge of said blank, adjacent to the point where the cutting is done, is made to bear upon a rigid support, 27, suitably fixed to a convenient part of the machine, a clamp 28 (not shown) being usually provided in connection with said support for clamping the blank thereon.

In the drawings, the master-index and its rotating-mechanism are shown protected by a cover, 28, secured to the bed of the machine by suitable screws; a supplemental cover or cap, 29, secured to the hub 10 of the master-index, being provided to cover the slight opening at the top of the cover 28 and prevent admission of dust and dirt.

As a means for determining the position of the master-index, and as a means for enabling the operator to bring the same accurately to the required position for making the graduations, I employ, in connection with the master-index and its operating means, a graduated reading indicator adapted for engaging the working-faces of the master-index and thereby showing with precision the location thereof. The graduated scale of said indicator, which will usually be a "vernier scale," constitutes the reading-scale of the machine, the mode of using which will be hereinafter more fully explained.

In the form thereof herein shown, the indicator, which is designated in a general way by L, is in the nature of a lever shown mounted upon a pivot or stud, 30, fixed on

the bed of the machine. This lever has a tooth, or actuating-arm, 31, located at one side thereof in position and adapted for bearing against the working-face, as, for instance, 5 the face designated by 1, of the master-index.

In the construction shown in the drawings, the indicator is actuated and controlled in its movements by the rotation of the master-index through the medium of the feeding-means 10 in connection with said index; but it is desired to state that said indicator might, with practicability, constitute a feed-lever for actuating or feeding the master-index, in which case the worm-wheel and worm constituting 15 the feed-mechanism hereinbefore described will be dispensed with, the indicator or feed-lever in this case being reciprocated to feed the master-index, together with the index-blank connected therewith, the requisite distance 20 for making the graduation. This reading indicator will have its indicating-end beveled to a knife-edge and provided with graduations after the manner of a vernier; a reading-scale, 35, being employed in connection 25 with said indicator to indicate the position of the master-index, as will be fully understood by reference to Figs. 1 and 4 of the drawings. The graduated scale 35 is shown as adjustably supported in a slide-way formed in a 30 block, 36, upon the bed of the machine, and as provided with adjusting-screws, 37, by means of which the position of the scale may be changed as desired.

In operating the machine, assuming the 35 actuating-arm 31 to be in working-contact with a working-face, as 1, of the master-index, as shown in full lines in Fig. 4, the index is turned forward in the direction of the arrow in said figure, by means of the feeding-mechanism hereinbefore described, which swings the indicator to the position shown in dotted lines in said figure, with its actuating-arm in position to engage the next succeeding working-face, 2, of said master-index; said indicator 40 being retracted or thrown into engagement with the successive working-faces by means of a spring, 38, secured at one end to an arm, 39, oppositely disposed with relation to the actuating-arm 31, and secured at its opposite end to the block 36 or bed of the machine. Said spring tends to normally retain the indicator with its operating-arm in constant bearing-contact with a working-face of the master-index, and is of such a nature 45 as to maintain a bearing-contact which will be of uniform pressure, so as not to affect the precision of the reading, which might vary to some slight extent if the pressure of the actuating-arm 31 against the working-face of the 50 master-index should vary. This retraction of the indicator, it will be understood, might be accomplished to secure the same results by a weight or other suitable retracting-device.

In ascertaining the correct position of the 55 master-index for marking the graduations, the said index is moved until the reading of the indicator coincides with the required cor-

rection designated by the working-table T of the respective working-face with which the actuating-arm of the indicator is engaged, 70 which working-faces are designated in the working-table by the numerals 1 to 24, inclusive, to coincide with the like designations in connection with the working-faces of the master-index. For instance, in position- 75 ing the master-index for making the first graduation, which is designated, alike in the working-table and upon the index, as 1, the indicator is set with its operating-arm in contact with the working-face 1. Reference is 80 then made to the working-table to ascertain the correction for the first graduation. In said table the first graduation is tabulated as 1-.0001, which indicates that the correct position for the first graduation is one ten-thousandth of an inch less than that first indicated by the position of the indicator as determined by the reading-scale. Therefore the indicator will be moved until the reading thereof will coincide with the registered cor- 90 rection on the working-table, which brings the master-index to the corrected position for graduating or marking the index-blank; which will be readily understood by those skilled in the art to which this invention ap- 95 pertains.

The indicator or feed-lever L herein shown and described is in the nature of a multiplier; and it is desired to state in this connection that I may substitute therefor any 100 other well-known form of mechanical multiplier adapted for multiplying the indications of the apparatus.

Having thus described my invention, I claim—

1. In a machine for the manufacture of precision-indexes, in combination, a master-index approximately divided into a given number of parts, which parts each have a working-face, a normally fixed reference-point or scale, and a reading-indicator in position and adapted for being shifted from and into bearing engagement with the successive working-faces, of the master-index and adapted to be read in connection with said reference point or scale, substantially as described.

2. In a machine for the manufacture of precision-indexes, a master-index approximately divided into a given number of aliquot parts, each part having a working-face, in combination with an indicator in position and adapted for operatively engaging the successive working-faces and having a reading-scale, and means for changing the position of said master-index, substantially as described and for the purpose set forth.

3. In a machine for the manufacture of precision-indexes, a revolvably-supported master-index radially divided peripherally into a given number of approximately aliquot parts, each part having a working-face, a multiplier or indicator in position and adapted for successively engaging said working-faces, a reading-scale in connection with said multiplier,

and means for rotating the master-index and for simultaneously changing the reading-position of the multiplier, substantially as described and for the purpose set forth.

5. 4. In a machine for the manufacture of precision-indexes, in combination, a master-index divided into a given number of approximately aliquot parts, each part having a working-face, an index-blank in rigid connection with said master-index, a multiplier or indicator in position and adapted for successively engaging the working-faces of the master-index and having a reading-scale, means for shifting the position of the master-index and 10 the index-blank, and means for marking or cutting the graduations or divisions upon the index-blank, substantially as described and for the purpose set forth.

5. In a machine for the manufacture of precision-indexes, the combination with the framework, of a revoluble spindle, a master-index secured to said spindle and divided into a given number of approximately aliquot parts, each part having a working-face, an index-blank in rigid connection with said spindle and master-index, feeding-mechanism in connection with said master-index, an indicator in position and adapted for successively engaging the working-faces of the master-index, a reading-scale in connection with the free end of said indicator, and means substantially as described for cutting or marking the graduations in the index-blank, substantially as described and for the purpose set forth.

35 6. In a machine for the manufacture of precision-indexes, a revolubly-supported master-index radially divided peripherally into a

given number of approximately aliquot parts and having a precision index-blank fixedly connected therewith, in combination with a pivotally-supported indicating-lever having an actuating-arm in position and adapted for operatively engaging the successive working-faces of the master-index, a reading-scale in connection with the indicating-end of said lever, means for rotating the master-index to bring successive working-faces into engagement with the actuating-arm of the indicator-lever, a shiftably-supported cutter or marker in position and adapted for cutting or marking the index-blank, and means for bringing said cutter into working position with relation to said blank, substantially as described and for the purpose set forth.

7. In a machine for the manufacture of precision-indexes, the combination with the frame-work, of a master-index divided into a given number of, approximately, aliquot parts, each having a working-face, an index-blank fixedly connected with said master-index and secured to a revoluble spindle, a worm-wheel secured to said master-index, a worm meshing with said worm-wheel, means for rotating said worm, a reading-indicator adapted for successively engaging the working-faces of said master-index, a cutter or marker revolvably carried upon a slide in position for cutting or marking the index-blank, and means for operating said cutter or marker, substantially as described and for the purpose set forth.

HERBERT C. WARREN.
